UNITED STATES PATENT OFFICE

169,135

CIGARETTE LIGHTER

Alfred Francis Fukal, Houston, Tex., assignor to
William A. Bruck, Denver, Colo.

Application April 25, 1952, Serial No. 19,474

Term of patent 3½ years

(Cl. D48—27)

To all whom it may concern:

Be it known that I, Alfred Francis Fukal, a citizen of the United States of America, residing at Houston, in the county of Harris and State of Texas, have invented a new, original, and ornamental Design for a Cigarette Lighter, of which the following is a specification, reference being had to the accompanying drawing, forming a part thereof.

In the drawing—

Figure 1 is a top plan view of a cigarette lighter showing my new design,
Figure 2 is a front elevational view of the same,
Figure 3 is a side elevational view of the same,
Figure 4 is a rear elevational view of the same,
Figure 5 is a bottom plan view of the same.

I claim:

The ornamental design for a cigarette lighter, as shown.

ALFRED FRANCIS FUKAL.
